United States Patent

Des. 240,135
Patented June 1, 1976

240,135

COMPUTER CONTROL PANEL

Kenneth C. Gorman, Mission Viejo, Robert E. Kopicki, Newport Beach, Joseph C. Reiss, Hemet, and Ronald E. Loosen, Malibu, Calif., assignors to Computer Automation, Inc., Irvine, Calif.

Filed Apr. 30, 1973, Ser. No. 355,936

Term of patent 14 years

Int. Cl. D14—02

U.S. Cl. D26—5 C

FIG. 1.

-75

FIG. 2.

-75

FIG. 3.

FIG. 4.

FIG. 5.

FIG. 1 is a top plan view of a computer control panel, showing our new design;

FIG. 2 is a front elevational view thereof;

FIG. 3 is a bottom plan view thereof;

FIG. 4 is a side elevational view thereof; and

FIG. 5 is a sectional view thereof, taken on line 5—5 of FIG. 2.

We claim:

The ornamental design for a computer control panel, as shown.
